UNITED STATES PATENT OFFICE.

WILLIAM R. PURNELL, OF THE UNITED STATES NAVY.

LIQUID-FUEL BURNER.

1,413,134.

Specification of Letters Patent. Patented Apr. 18, 1922.

Application filed June 22, 1920. Serial No. 390,769.

To all whom it may concern:

Be it known that I, WILLIAM R. PURNELL, a lieutenant commander in the United States Navy, a citizen of the United States, at present stationed at Philadelphia, in the county of Philadelphia and State of Pennsylvania, have invented certain new and useful Improvements in Liquid-Fuel Burners; and I do hereby declare the following to be a full, clear, and exact description of the invention, such as will enable others skilled in the art to which it appertains to make and use the same.

This invention relates to liquid fuel burners and has for its object to provide a burner which will utilize the heat and the velocity of the atomizing agent, as well as the velocity of the liquid fuel in securing a high degree of fineness of atomization in the spray, in order to improve the combustion, to increase the efficiency and to reduce the consumption of the atomizing agent.

With these objects in view the invention consists in the novel details of construction and combinations of parts more fully hereinafter disclosed and particularly pointed out in the claims.

Referring to the accompanying drawings forming a part of this specification, in which like numerals designate like parts in all the views:

Figure 1 is a side elevational view partly in section of a burner made in accordance with this invention;

Figure 2 is an end elevational view of the parts shown in Figure 1;

Figure 3 is a sectional detail view of the tip of the burner;

Figure 4 is a view taken on the line 4-4 of Figure 3, looking in the direction of the arrows;

Figure 5 is a sectional view of a slightly modified form of the cap portion of the burner tip; and

Figure 6 is an end view of the cap shown in Figure 5.

1 represents any suitable liquid fuel supply, 2 a valve controlling said supply, and 3 a chamber to which said supply leads; 4 represents a casting, 5 a supply of steam or compressed air, 6 a valve controlling said last named supply, and 7 a channel or opening in the casting 4 to which said supply leads. 8 indicates a pipe member screw threaded in the casting 4 as at 9, provided with the internal passage 10, and with the

external screw-threads 11, affording the helically disposed passages 12. An outer pipe 13 is at one end screw threaded into the casting 4 as at 14, and encloses said inner pipe 8, and at its outer end it is screw threaded into the cap member 15. Between the extreme outer end 16 of the pipe 13, and the abrupt shoulder 17 with which the cap 15 is provided, there is located a copper washer 18 provided with the holes 20, all as will be clear from Figure 3. Fitting the end 19 of the pipe 8 is the reduced end of the plug 21, having a shoulder 22 corresponding to the shoulder 17 and between said end 19 and said shoulder 22, the copper washer 18 also fits, so that a tight joint between the pipes 8 and 13 and the cap 15 is provided.

The channel 10 containing steam communicates with the bore 23 of the plug 21, and the helical passages 12 and space surrounding the same communicate through the orifices 20 with the grooves 25 located on the inside of the cap 15, as well as with the recess 26 with which said cap is provided. Said grooves 25 are formed between the members 27 located on the inside of said cap 15, and are closed on one side by the plug 21 which fits said members 27, all as is plainly shown in Figures 1, 3, and 4.

After reaching the recess 26 through said channels 12 and grooves 25, the fuel passes through the tangentially disposed channels 30, with which the extreme outer end of the plug 21 is provided, and to the chamber 31 into which said channels 30 lead. Owing to the pressure on said fuel and to the tangential disposition of said channels 30, the fuel is whirled or rotated at a high velocity in the chamber 31. The bore 23 of the plug 21 opens in said whirling or mixing chamber, and therefore conveys steam or air under pressure thereinto. The chamber is closed except for the relatively small outlet 35, and therefore a most thorough mixing of steam or air and fuel, and a most thorough atomization of said fuel takes place in said chamber 31.

It will now be seen that by passing hot steam under pressure on the inside of pipe 8, and passing fuel under pressure through the grooves 12, I divide the fuel into thin streams, or films, while subjecting them to a considerable temperature; and I thus lower the viscosity of the fuel and promote the atomizing action. Further, by providing

the continuous screw threads shown I am enabled to get a maximum of heated surface over which the fuel flows, and to thus break down the surface tension of the oil to a greater degree than would otherwise be possible. It will be likewise observed, that the full velocity of the oil is utilized in causing a swirling motion in the presence of steam in the chamber 31, while the full velocity of the steam is utilized in carrying said oil out of said chamber past the sharp edges of the orifice 35 to the point of ignition. The result is an unusually perfect atomization of the fuel and therefore a most satisfactory spray is delivered to the combustion chamber, not shown.

What I claim is:—

1. In a liquid fuel burner the combination of means adapted to conduct a fluid atomizing agent under pressure; a helical screw thread on the exterior of said conducting means, for dividing the fuel into relatively thin films or streams; means to supply said atomizing agent to said conducting means; means to supply fuel to said screw thread; and a plug having a mixing chamber, a bore connecting said conducting means with said chamber, and a plurality of tangentially disposed passages adapted to conduct fuel delivered from said screw thread to said chamber.
2. In a liquid fuel burner the combination of means provided with a passage, adapted to conduct steam under pressure; a helical screw thread on the exterior of said conducting means, for dividing the fuel into relatively thin films or streams, while subjecting said fuel to the action of the heat of said steam; means comprising a valve controlled pipe, to supply steam to said passage; means to supply fuel to said screw thread; a plug provided with a mixing chamber, a bore connecting said passage with said chamber, and a plurality of tangentially disposed passages leading to said chamber; and a cap member provided with passages affording communication between said screw thread and said tangential passages.
3. In a liquid fuel burner the combination of an inner pipe provided with external screw threads; an outer pipe enclosing said inner pipe; a casting to which one end of each of said pipes is secured; a plug member fitting the other end of said inner pipe and provided with a mixing chamber; a cap pro-

vided with grooves enclosing said plug and secured to the other end of said outer pipe; a perforated washer member located between the end of said outer pipe and said cap; means for passing steam under pressure through said inner pipe, plug and chamber; and means for passing oil under pressure between said screw threads and through said grooves and chamber whereby the velocities of said oil and steam are utilized in effecting an atomization and the heat of said steam is used in breaking down the viscosity of the oil, substantially as described.

4. In a liquid fuel burner the combination of an inner pipe provided with external screw threads; an outer pipe enclosing said inner pipe; a casting to which one end of each of said pipes is secured; a plug fitting the other end of said inner pipe and provided with a mixing chamber and with a plurality of tangentially disposed passages leading thereto; a cap secured to the other end of said outer pipe and provided with a plurality of grooves connecting said screw threads and said tangential grooves; an orifice having sharp edges in said cap opening into said chamber; a perforated washer member located between the end of said outer pipe and said cap; means for passing steam under pressure through said inner pipe, plug, and chamber; and means for passing oil under pressure between said screw threads through said grooves and chamber whereby the velocities of said oil and steam are utilized in effecting the atomization of said oil, and the heat of said steam is used in breaking down the viscosity of said oil, substantially as described.

5. In a liquid fuel burner the combination of means provided with a passage adapted to conduct a fluid atomizing agent under pressure; a pipe surrounding said conducting means and spaced therefrom to provide a passage adapted to conduct fuel; means rigid with said first named means for imparting a rotary motion to said fuel; means to supply said atomizing agent to said first named passage; means to supply fuel to said second named passage; a plug fitting said first named passage and provided with a mixing chamber; and connections between said chamber and each of said passages, substantially as described.

In testimony whereof I affix my signature.

WILLIAM R. PURNELL.
